UNITED STATES PATENT OFFICE.

JOHN L. SQUIRE, OF MENOMONIE, WISCONSIN.

RAIL-JOINT.

1,199,627.

Specification of Letters Patent. Patented Sept. 26, 1916.

Application filed May 25, 1915. Serial No. 30,389.

To all whom it may concern:

Be it known that I, JOHN L. SQUIRE, a citizen of the United States, residing at Menomonie, in the county of Dunn and 5 State of Wisconsin, have invented new and useful Improvements in Rail-Joints, of which the following is a specification.

The present invention relates to means for connecting the meeting ends of two 10 railway rails.

In carrying out my invention it is my purpose to provide rail engaging means wherein the base portion upon which the rails lie will be of a materially greater 15 thickness than the remaining rail engaging elements of the same, and further wherein the vertical plates which contact with the sides of the rail shall be beveled or inclined upon their outer faces from their upper 20 rail head receiving portions to their juncture with the flanged portions which overlie the base flanges of the rails, so that the base of said members will be of a materially greater strength than the said upper and 25 rail engaging portions to permit of the yieldability of the said upper portions so that the same may be snugly arranged into contact with the said underfaces of the rail and also to permit of the said members 30 gradually increasing in strength from the juncture of said flanged portions which, as stated, overlie the flanges of the rails.

With the above and other objects in view, the improvement resides in the construction, combination and arrangement of parts 35 set forth in the following specification and falling within the scope of the appended claim.

In the drawing: Figure 1 is a perspective 40 view of two rails connected in accordance with the present invention, and Fig. 2 is a transverse sectional view through the same.

Referring now to the drawings in detail, the numerals 1-1 designate two rails of 45 the ordinary construction connected in accordance with my invention.

My connecting means includes a pair of chair members, each comprising a base 2 which is of a materially greater thickness 50 and consequently of a greater strength than the remainder of the device. The base 2 of each of the members of the chair adjacent its outer longitudinal edge is formed with a vertical extension 2' of a materially

less width than that of the base, and formed 5 integral with the said extension 2' and providing an extension therefor is an angular plate 3, which is adapted to overlie the base flanges of the rails. Each of the flanges 3 comprises a comparatively thin plate, and to add 60 to the yieldability thereof I channel the said flanges 3 upon their underfaces throughout their length as indicated by the characters 3'. The edges of the base 2 projecting beyond the portions 2' of the overlying flanges 3 are notched, as at 4, to permit of the heads of spikes contacting with the comparatively thin flanges to compress the same 65 toward the rails.

Arising vertically from the inner longitudinal edges of the plates 3 which overlie the base flanges of the rails 1, are vertically disposed plates 5, the inner faces of said plates being straight and the inner corners of the plates are formed with longitudinally extending ribs 3''. The outer faces of 75 the vertical members 5 from the upper edges thereof are beveled or inclined downwardly and outwardly to their juncture with the flanges.

The plates 5 as well as the webs of the rails are provided with the usual holes for the reception of the ordinary securing elements in the nature of bolts and nuts therefor.

From the above description, taken in connection with the accompanying drawing, the simplicity of the device, as well as the advantages thereof will, it is thought, be perfectly apparent to those skilled in the 90 art to which such invention appertains without further detailed description.

Having thus described the invention, what I claim is:

The combination with a railway rail, of 95 a chair comprising a pair of similarly formed members each consisting of a thickened base portion, an upwardly and laterally extending and thinner flange disposed over the base portion to receive the base of the rail therebetween, a vertical and upwardly tapering web portion on the free end of the flange, a rib formed at the juncture of the web portion with the flange and extending downwardly, into contact with 100 the upper face of the rail base, said flange being spaced above the base of the rail between the said rib and the upwardly ex-

tending portion of the flange, said chair member being formed with spike receiving notches at the juncture of the flange and base, and spikes disposed in said notches and adapted to compress the thinner flange portion against the base of the rail at points adjacent the said notches.

In testimony whereof I affix my signature in presence of two witnesses.

JOHN L. SQUIRE.

Witnesses:

ROBERT HEIDEN,
WILLIAM C. LINK.
